Primary Examiner — Cynthia M. Chin(74) *Attorney, Agent, or Firm* — Master Key IP, LLP;
Justin G. Sanders(57) **CLAIM**

The ornamental design for an inflatable building block, as shown and described.

DESCRIPTION

FIG. 1 is a perspective view showing a first embodiment of my new inflatable building block design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing a second embodiment of my new inflatable building block design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

In FIGS. 8-14, the appearance of any portion of the article between the break lines forms no part of the claimed design.

1 Claim, 8 Drawing Sheets(56)
